DESIGN FOR A COMBINED SHELF AND MIRROR UNIT

Charles Daum, Forest Hills, Long Island, N. Y.

Application December 13, 1941, Serial No. 104,624

Term of patent 3½ years

To all whom it may concern:

Be it known that I, Charles Daum, a citizen of the United States and a resident of Forest Hills, Long Island, in the county of Queens and State of New York, have invented a new, original, and ornamental Design for a Combined Shelf and Mirror Unit, of which the following is a specification, reference being had to the accompanying drawing, forming part thereof, in which:

bined shelf and mirror unit embodying my new design.

Figure 2 is an end elevational view of the same.

The dominant features of the design reside in the portions shown in full lines.

I claim:

The ornamental design for a combined shelf and mirror unit, as shown and described.

CHARLES DAUM.
